CLAIM

The ornamental design for a lip product container, as shown and described.

DESCRIPTION

FIG. 1 is a front perspective view of a lip product container in an open configuration showing our design; FIG. 2 is front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines shown in FIG. 7 immediately adjacent to claimed subject matter depicts a boundary of the lip product container that forms no part of the claimed design. The broken lines in FIGS. 2–5 depict portions of the lip product container which form no part of the claimed design. None of the broken lines form no part of the claimed design.
